(57) **CLAIM**

The ornamental design for an electrical box and conduit support plate, as shown and described.

DESCRIPTION

FIG. 1 is a top perspective view of the new design for an electrical box and conduit support plate;

FIG. 2 is a first side elevation thereof;

FIG. 3 is a second side elevation thereof;

FIG. 4 is a top plan view thereof; and,

FIG. 5 is a bottom plan view thereof.

The broken lines shown represent portions of the support plate that form no part of the claimed design. Where the dot-dash broken lines abut the shaded surface it is understood that those broken lines represent an unclaimed boundary between claimed and unclaimed surfaces.
